US00D776988S

(12) **United States Design Patent** (10) **Patent No.:** **US D776,988 S**
(45) **Date of Patent:** **** Jan. 24, 2017**

(54) **FOOD CUTTING DEVICE**

(71) Applicant: **Genius GmbH**, Limburg (DE)

DE 8525144 U1 3/1986
DE 212005000048 U1 5/2007

(72) Inventor: **Cedomir Repac**, Brechen (DE)

(Continued)

(73) Assignee: **GENIUS GMBH**, Limburg (DE)

(**) Term: **14 Years**

(21) Appl. No.: **29/525,071**

(22) Filed: **Apr. 27, 2015**

(74) *Attorney, Agent, or Firm* — Leydig, Voit & Mayer, Ltd.

(57) **CLAIM**

The ornamental design for a food cutting device, as shown and described.

DESCRIPTION

FIG. 1 is a top front right perspective view of a first embodiment of a food cutting device showing my new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan top view thereof;

FIG. 7 is a bottom plan view thereof;

FIG. 8 is a top front right perspective view of a second embodiment of a food cutting device showing my new design;

FIG. 9 is a right side elevational view thereof;

FIG. 10 is a left side elevational view thereof;

FIG. 11 is a front elevational view thereof;

FIG. 12 is a rear elevational view thereof;

FIG. 13 is a top plan top view thereof; and,

FIG. 14 is a bottom plan view thereof.

(Continued)

The broken lines shown in FIGS. 1-14 represent portions of the food cutting device that form no part of the claimed design.
